(57) **CLAIM**

The ornamental design for a chair, as shown and described.

DESCRIPTION

FIG. 1 is a front, left, and top perspective view of a chair of my design.

FIG. 2 is a rear, left, and bottom perspective view of the chair of FIG. 1.

FIG. 3 is a front view of the chair of FIG. 1.

FIG. 4 is a rear view of the chair of FIG. 1.

FIG. 5 is a first side view of the chair of FIG. 1.

FIG. 6 is a second side view of the chair of FIG. 1.

FIG. 7 is a top view of the chair of FIG. 1; and,

FIG. 8 is a bottom view of the chair of FIG. 1.

The dash broken lines are for the purpose of illustrating environmental structure that forms no part of the claimed design.

1 Claim, 8 Drawing Sheets*FIG. 1*

FIG. 2

FIG. 3

FIG. 4

FIG. 5

FIG. 6

FIG. 7

FIG. 8
